UNITED STATES PATENT OFFICE.

SEBASTIANO RIZZA, OF HARTFORD, CONNECTICUT.

COMBINED DIESTOCK AND TAP WRENCH.

Application filed June 21, 1923. Serial No. 646,928.

To all whom it may concern:

Be it known that I, SEBASTIANO RIZZA, a citizen of the United States, and a resident of Hartford, in the county of Hartford and State of Connecticut, have invented certain new and useful Improvements in a Combined Diestock and Tap Wrench, of which the following is a specification.

10 This invention relates to a die stock and tap wrench for holding both dies and taps. One of the objects of the invention is to provide an improved form and arrangement of parts for a combined tap wrench and die stock.

20 Another object of the invention is to provide an improved device of this character which may be used for holding either a thread cutting die or a tap and which is adjustable for the purpose of holding taps having various sized shanks.

25 Another object of the invention is to provide an improved form of combined die stock and tap wrench in which a tap of any desired size may be held without disturbing or removing the die from the die stock.

30 Another object is to provide an improved unitary structure for a combined die stock and tap wrench, which is convenient, easy to operate, strong, durable and inexpensive to manufacture.

35 Other objects and advantages of the invention will be in part obvious and in part pointed out hereinafter.

40 The invention accordingly consists in the features of construction, combination of elements and arrangement of parts which will be exemplified in the construction hereinabove set forth, and the scope of the application of which will be indicated in the appended claims.

45 In the drawing forming a part of this specification and in which similar reference characters refer to similar parts—

Figure 1 is a plan view of a combined die stock and tap wrench embodying the features of the invention;

50 Figure 2 is a longitudinal section of the device shown in Figure 1 indicating the operation of the various parts;

Figure 3 is an underside plan view of the same device;

55 Figure 4 is an end view taken along the line 4—4 of Figure 1;

Figure 5 is a sectional view taken along the line 5—5 of Figure 1; and

Figure 6 is a view of the device, all the parts being detached, and the method of assembling being indicated.

60 Referring to the drawings, the device comprises a body portion 10 with suitable arms 11 and 12 disposed at either side for rotating the body, and provided on one side with an orifice as at 13 to receive a die, 65 and on the other side having a stationary jaw 14 which, with a movable or clamping jaw 15, is adapted to grip the end of a tap, reamer, or other similar tool.

65 The orifice 13 is suitably shaped to receive a die and may be circular or any other desired form. It extends part way into the body 10 to a depth substantially equal to the thickness of the die to be held. The die is held within this orifice by suitable 70 means, such as set screws 16, which are adapted to screw through the body 10 and wedge the die in place.

75 On the side of the body 10 opposite the orifice 13, the body is cut away to form a 80 jaw 14 integral with the body and to provide space for the clamping jaw 15 to be moved back and forth. The jaw 15 is in the form of a slide having stepped side edges as at 17 to engage with the sides of a groove 85 extending longitudinally of the body 10 as at 18 (Fig. 4). The jaw 15 is thus slidable in the direction of and away from the stationary jaw 14. Suitable means are provided for moving this jaw backward and 90 forward, such as the threaded end 19 of the arm 12 which is arranged to engage a threaded part 20 on the jaw. The arm 12 is reduced somewhat at the threaded end 19, as indicated at 21, leaving a shoulder at 95 each end of the thread 19. The body 10 is cut away, as at 22, to receive the reduced portion of the arm 12, and is cut away slightly deeper at 23 to receive the threaded part 19 of the arm. Between these two cut 100 away parts 22 and 23 there is formed a shoulder 24 against which the forward end of the threaded portion 19 abuts to form an end thrust bearing. A thrust bearing for the other end of the threaded part 19 is provided by a plate 25 which is generally rectangular, being cut away as at 26 to permit the jaw 15 to slide therethrough. The plate 25 is held in place against the body 10 by means of screws 27.

The operation of the device, as a tap wrench, may be understood from the foregoing description. It will be noted that upon rotation of the arm 12, the clamping 5 jaw may be moved to engage a tap or similar tool in cooperation with the stationary jaw 14. Upon rotation of the arm 12 in the opposite direction, the jaw 15 may be withdrawn and the tap removed.

10 Among other advantages, it will be noted, that in order to use the device as a tap wrench, it is not necessary to remove the die, since this does not interfere with the operation of the tap in any way.

15 It will also be noted that none of the parts of the combined structure need be removed in order to use it for any of the purposes for which it is designed, and that, therefore, there is not the danger of parts 20 being mislaid and lost, or any loss of time in adapting it for the desired operation. If the tap is of comparatively small diameter, its center will be somewhat out of the center of the body 10 which will cause 25 a slight unbalancing of the device. This may be compensated by unscrewing the handle 28 on the arm 11 so that it projects further from the center of the body 10. In this manner also the leverage provided by the two arms may be balanced 30 so that a more nearly equal pull may be had on each side when the tap is not exactly at the center of the body.

If it be desired to use a die of an outer 35 diameter smaller than the orifice 13, such as for instance, that indicated at 29, a ring or bushing 30 may be inserted with the die in the orifice to fill the excess space. The ring 30 will have diametrically spaced openings 31 through which the inner ends of 40 the screws 16 will protrude to engage the periphery of the die 29.

Thus by the above construction are accomplished, among others, the objects hereinbefore referred to.

45 As many changes could be made in the above construction and many apparently widely different embodiments of this inven-

tion could be made without departing from the scope thereof, it is intended that all 50 matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a device of the character described, a body portion comprising an integral block having a through opening providing at one 65 side of the block a recess or seat adapted to receive a die, a die in said seat, jaws on the other side of said block adapted to extend into the end of the opening opposite said seat, one of said jaws being integral 70 with said block and forming a shoulder constituting the bottom of said die seat, the other of said jaws being dovetailed into said block for sliding movement towards and away from said first jaw, a pair of 75 arms extending from said block for turning the device, and a connection between one of said arms and said slidable jaw for adjusting the latter.

2. In a device of the character described, 80 a body portion, a pair of relatively movable jaws thereon adapted to engage a tap, a pair of arms extending in opposite directions from said body portion and each provided at its outer end with a handle, 85 one of said arms being rotatable, means between said rotatable arm and one of said jaws for adjusting said jaw when said arm is rotated, and a threaded connection between said rotatable arm and its handle 90 whereby the latter may be adjusted longitudinally of said arm to balance the device, said rotatable arm being fixed against longitudinal movement relative to said body portion.

SEBASTIANO RIZZA.
